CHRISTMAS ORNAMENT

Ralph O. Johnson, Bristol, Conn., assignor to Associated Spring Corporation, Bristol, Conn., a corporation of Delaware

Application August 18, 1955, Serial No. 37,558

Term of patent 14 years

(Cl. D29—1)

Fig. 1

Fig. 1 is a side elevational view of a Christmas ornament showing my new design;

Fig. 2 is a top plan view of the ornament shown in Fig. 1; and

Fig. 3 is a bottom plan view of the base portion of the ornament shown in Fig. 1.

I claim:

The ornamental design for a Christmas ornament, as shown.
